UNITED STATES PATENT OFFICE.

DAVID H. MCFALLS, OF ELLENSBURG, WASHINGTON.

CARPET STRETCHER AND TACKER.

SPECIFICATION forming part of Letters Patent No. 512,659, dated January 9, 1894.

Application filed March 24, 1893. Serial No. 467,409. (No model.)

To all whom it may concern:

Be it known that I, DAVID H. MCFALLS, a citizen of the United States, residing at the city of Ellensburg, county of Kittitass, State 5 of Washington, have invented a new and useful Improvement in Carpet Stretchers and Tackers, of which the following is a specification.

My invention relates to improvements in devices for stretching and tacking carpets, and the object of my invention is to produce a machine by means of which a carpet may be stretched and at the same time be tacked to the floor while held in its distended position. I attain this object by means of the mechanism illustrated in the accompanying drawings, in which—

Figure 1 is a plan. Fig. 2 is a side elevation of the hammer raised. Fig. 3 is a side elevation of the hammer down. Fig. 4 is a vertical section through the feeding device. Fig. 5 is a horizontal section along the lines I—I on Fig. 4. Fig. 6 is a detail view of the cup L showing said cup closed. Fig. 7 is a detail view of the cup L showing the cup open, and Fig. 8 is a cross section of the feeding tube N.

Similar letters refer to similar parts throughout the several views.

The body A of my stretcher is constructed of a block of wood or other suitable material, having upon its lower surface, that which comes into contact with the carpet, a corrugated rubber covering a, or if desired, the lower surface of the block a may be serrated or provided with serrated strips of rubber, or other suitable material, in order that the carpet upon which the stretcher is placed may be seized upon by the stretcher in such a manner that the movement of the stretcher will tend to carry with it the carpet upon which it is placed.

At about the center of the upper surface of the block A, I secure the handle B by means 45 of the hinge b. Near the rear end of the block A, I secure one end of the hammer C by means of the bolt c, making a hinged joint. The hammer shank C moves within the slot D within the handle B. At the end 50 of the hammer shank C, I secure the bifurcated weighted hammer head E. Near the lower end of the hammer shank C, I secure the

rod F, which is attached to the sliding collar G, which collar G surrounds the handle B and reciprocates freely upon said handle. 55 Near the lower end of the shank of the hammer G, and on each side thereof arranged in pairs I secure the rods H, which are attached to one arm of the bell crank lever J; said bell crank lever being secured to the block 60 A near the front and on each side thereof, the rods H and their attachments being arranged in pairs; the feeding mechanism being also arranged in pairs. I will describe one of each. The arm k of the bell crank 65 lever J opposite that to which the rod H is attached is provided with a sharpened upwardly projecting point, which comes into contact with the carpet near its edge when the stretching process is being carried on. 70 The bell crank lever J, arranged in pairs at the front of the block A, is thus arranged in such a manner that the upwardly projecting point K will come into contact with the carpet near its edge and when the hammer is 75 raised, will hold the carpet at the edge to be nailed, slightly above the floor. The hand of the operator is used to hold the hammer in a raised position, which is done by grasping the reciprocating collar G, and holding it when 80 the strain of the carpet would tend to pull down the prongs of the hammer with them. When the hammer is allowed to descend it is usually forced downward by the hand of the operator, and the carpet is by the upwardly 85 projecting point K of the bell crank lever, forced forward and in position for the tack in the feeding mechanism to be driven into the carpet.

To the forward end of the block A immediately beneath the weighted hammer E, I arrange the cup L composed of two pieces of tin, or other suitable metal, made in the form of a truncated cone, so constructed that the two pieces forming the cap may be separated 90 laterally and having attached to the sides of each piece one of the arms of a flat steel spring l; the operation of the spring l being to hold the two portions of the cup L together, the spring l being secured to the base plate M of 95 the feeding mechanism.

To the base plate M of the feeding mechanism in front of the cup L, I attach the guiding spring m, which is a very narrow strip of 100

metal extending into the cup L immediately in front of the opening of the tube N into said cup and arranged in such a manner that the tack entering the cup L from the tube N, 5 will come into contact with the guiding spring m and the head of the tack will rest upon the guiding spring m in position to be operated upon by the hammer bolt E'.

Extending from near the top of the cup L 10 in an upwardly inclining position, I arrange the tube N provided on its under side with a slot n, the sides of the slot n opening outward and downward, as shown in cross section in Fig. 8. The slot n communicates with 15 the cup L at its upper surface.

Extending upward from the base plate M immediately above the cup L, I arrange in the cylinder O, a hammer bolt E' provided with a collar e and a spiral spring e', by the 20 operation of which the resiliency of the spring will hold the bolt in the position shown in Fig. 4, the lower end of the bolt above the cup L.

The bolt E' is constructed of such a diameter as to allow of its entrance into the cup L for the purpose of driving the tack within the cup L into the carpet and floor. The entrance of the bolt E' into the cup L will cause the two lateral portions of the cup L 25 to separate against the tension of the spring l. The guide spring m will be drawn away from contact with the head of the tack and the force of the blow of the hammer upon the hammer bolt E' will perform the required 30 result of nailing the carpet onto the floor. When the spring e' causes the bolt E' to be raised from the cup L, the tack in the tube N nearest the cup L will fall into the cup L and come in contact on one side with the guiding spring m. In order to keep the remaining tacks within the tube N in position, I arrange the stud P to the spring l on one side of the tube N, as shown in Fig. 5, in such a manner that it will enter the lower portion of 35 the tube N and be placed in front of the shank of the first tack within the tube N. When the hammer bolt E' opens the cup L, the spring l being expanded, the stud p will be drawn out of contact with the tack and 40 that tack will fall in contact with the bolt E', as shown by dotted lines in Fig. 4. The tack next above it will come down in contact with the first tack in this new position. When the bolt E' is raised above the cup L, the 45 first tack will fall into the cup and the stud p will enter the tube N and retain the first tack in the tube.

The operation of my apparatus is apparent at a glance. I place the stretcher upon the 50 carpet near the edge. The hook K at the end of one arm of the bell crank lever engaging with the carpet. The surface of the block A being of such a nature as to attach itself to the carpet without tearing it. The carpet 55 is then stretched when the handle B is pushed upon; and in order to get a purchase

for forcing the stretcher and the carpet in connection therewith along the floor I place the arm S, having one end pivotally secured to the block s in contact with the base 70 board on the side of the room opposite that upon which the stretcher is placed. There are suitable rests T extending from the surface of the arm S in contact with which the end of the arm B of the stretcher is brought, 75 as shown in Fig. 2. A band U is placed over the arm S provided with a loop into which the foot may be placed. Then by drawing downward upon the arms S and B the stretcher block A will be forced out, moving 80 the carpet in the direction required. For the purpose of nailing the carpet in position, the collar G is drawn toward the end of the arm B, the rod F thus lifting the hammer and at the same time the rod H attached to the bell 85 crank lever J lifts the edge of the carpet and holds it securely in position. When the carpet is stretched to the desired extent, the collar G is forced along the handle B toward the stretcher, causing the carpet to be released from contact with the end of the bell crank lever and fall down in front of the stretcher and at the same time the bolt E' 90 will be driven by the hammer E into the cup L and drive the tack contained therein into 95 the carpet and the floor.

My invention is extremely simple in its construction and operation and performs the work required of it in a positive and satisfactory manner.

I do not limit myself to the exact construction of the tack feeding device, since I may do without the cup L constructed in the form shown.

I do not limit myself to the hammer head 105 constructed in the exact form shown.

What I claim as my invention, and desire to secure by Letters Patent, is—

1. In a carpet stretcher, the combination of a block placed in contact with the carpet, an 110 arm pivoted to said block, a hammer pivoted to said block, a bell crank lever, a rod connecting one arm of said bell crank lever to the shank of said hammer, the other arm of said bell crank lever being adapted to engage with the carpet, a reciprocating collar upon said arm, a rod connecting said collar with the shank of said hammer, substantially as described and for the purpose set forth.

2. In a carpet stretcher, the combination of 120 a block adapted to rest upon the carpet, a hammer pivoted to said block, an arm pivoted to said block, a bell crank lever pivoted to said block, a rod connecting one arm of said bell crank lever with the shank of said 125 hammer, the other arm of said bell crank lever adapted to engage with the carpet near its edge, a collar placed upon said arm, a rod connecting said collar with said hammer shank, a cup secured to the front end of said 130 block, a slot along the surface of said cup nearest the block, a slotted tube connecting

with said cup adapted to receive tacks, substantially as described and for the purpose set forth.

3. In a carpet stretcher and tacker, the combination of a block, a hammer pivoted thereto, an arm pivoted to said block, with a tack feeding mechanism consisting of a cup open at the top and bottom, a tube communicating with said cup, a guide spring, a spring operated by the separating of the sides of the cup, a stud attached to said last mentioned spring by the operation of which the tacks are held within the tube, substantially as described and for the purpose set forth.

15 4. In a carpet stretcher, the combination of a block placed in contact with the carpet, an arm pivoted to said block, a hammer pivoted to said block, a bell crank lever, pivoted to the front of said block a rod connecting one

arm of said bell crank lever to the shank of 20 said hammer, the other arm of said bell crank lever being adapted to engage with the carpet, a reciprocating collar upon said arm, a rod connecting said collar with the shank of said hammer, a plate fastened across the face of 25 said block, adapted to engage with the carpet, with a rest consisting of an arm hinged to a block adapted to be brought in contact with the base board opposite to that toward which the carpet is to be stretched, with projections 30 on said arm adapted to receive the end of the stretcher arm, substantially as described and for the purpose set forth.
